DISPLAY AND DISPENSING MEANS

Edward Ezrol, Brooklyn, N. Y., assignor to
Herbert Robinson and Otto A. Golluber, doing
business under partnership name Robinson and
Golluber, New York, N. Y.

Application February 1, 1941, Serial No. 377,027

1 Claim. (Cl. 312—39)

The present invention is concerned with new and improved means for the displaying and dispensing of lace, ribbons and similar materials.

Desiderata in devices for displaying and dispensing lace, ribbon, braid and the like are, among other things:

(a) That the value of the material being displayed and to be dispensed be protected against substantial impairment due to soiling or other prejudicial influence, i. e. that the material be kept absolutely clean;

(b) That the housing or containers for the material, which is generally housed in reel form, be of a character such as to facilitate unwinding and rewinding of the material;

(c) That a substantial strip or portion of the material be exposed to view so that prospective purchasers may appreciate the design, colorings or other qualities thereof;

(d) That a plurality of containers or housings for the material be capable of juxtaposition either on conventional shelving or on specially-constructed racks so that the lace or other strip material may be displayed in related or contrasted sets, if desired;

(e) That exhausted containers of a display set may be replenishable or replaceable without difficulty and without essentially disturbing other containers;

(f) That the several containers be capable of use per se, as distinguished from use in association with other containers;

(g) That means be provided for fixing or locking the display material in adjusted position in the periods between dispensing operations; etc.

A primary object of the present invention is the realization of novel and improved relationships of parts which embody the above enumerated desiderata and also present other and further advantages which will become readily apparent as the following detailed description of a presently-preferred exemplary embodiment of the invention progresses.

In order that the invention may more readily be understood, the following detailed description is set forth with reference to the illustrative showing on the accompanying sheets of drawings, wherein:

Fig. 1 illustrates, in perspective, one method of reducing the present invention to practice, showing the requisite means in this regard;

Fig. 2 is a cross sectional view, on a relatively enlarged scale, through a container, according to this invention and through the adjacent supporting rack parts;

Fig. 3 is a partial perspective view, also on a relatively enlarged scale, of a detail according to the invention;

Fig. 4 is a top plan view of the interior of a specimen blank for the production of a container in accordance with the present invention.

Referring first to the supporting wire frame or rack shown more particularly in Fig. 1 of the drawings, this frame comprises substantially L-shaped skeleton end members 1 and 2 interconnected by transverse struts 3, 4, 5, 6, 7, 8, 9, 10, 11, 12 and 13 extending therebetween.

The L-shaped configuration of these end members makes it possible to provide two relatively off-set supporting shelves positioned at different levels, one shelf being arranged essentially in alignment with the lower horizontally projecting portion of the L, while the other is arranged at the top of the vertical portion of the L. The bottoms of these shelves are defined, respectively, by transverse struts 3 and 4 in the one case, and by transverse struts 9 and 10 in the other.

Struts 3 and 4 are connected at their respective ends to rods 14 and 15 which extend across the lower part of end walls 1 and 2 in a direction substantially parallel to the bottom of the said walls.

Transverse struts 9 and 10 are connected at their respective ends to rods 16 and 17 which extend in substantially parallel relationship to rods 14 and 15 across the upper part of end walls 1 and 2 as illustrated.

Containers 18 for reels of lace, ribbons or the like to be displayed and/or dispensed may be supported in close adjacency to each other, if desired, on the shelf bottoms thus defined by struts 3 and 4 and 9 and 10 respectively.

While undesired relative displacement of the containers 18 will normally be prevented by means extending therethrough as hereinafter disclosed, auxiliary means preventing said displacement of the several containers may be provided in the form of struts 6 and 11.

Similarly, "skeleton shelf tops" may be defined by pairs of struts 7, 8 and 12, 13 respectively. While struts 8 and 13, the latter being of inverted elongated U-configuration, extend between the skeleton end walls 1 and 2 of the device, struts 7 and 12 preferably extend between price-tag supporting uprights 19, 19 and 20, 20 respectively, these being severally positioned as shown on Fig. 1 of the drawings. The several upper ends of uprights 19 and 20 are bent back to a somewhat inclined position to provide means for the mounting of price-tag bars 21, 21. These may con-

veniently be made of strips of sheet metal, the longitudinal edges 22 of which may be flanged or bent over to provide tag receiving channels. These flanges preferably terminate short of the sheet metal strips where the latter are bent into the form of substantially cylindrical sleeves 23 adapted to fit over and upon the upper ends of uprights 19 and 20. Price tags 24 may be arranged in the aforesaid channels in alignment with the corresponding lace or other displayed material to be identified thereby.

Substantially elongated U-shaped rods 25 depend from the tag-holding strips to which they may be secured as at 26. Any suitable securing means such as solder or the like may be used for affixing the various above- and hereinafter-disclosed parts of the display rack to each other. It will, of course, be understood that these several parts are preferably made of suitable metal.

A locking bar 27, which preferably serves simultaneously as a journal for the reels of lace or other material in the several containers 18, is provided for each display series or sets. This bar consists essentially of a rod, preferably of a slightly larger cross sectional diameter than the rods which constitute the display rack, either end of the locking bar being bent substantially at right angles, as shown, to provide a handle 28. Means are provided on the display rack for supporting the locking bars 27. Thus, journal loops 29, 29 are provided, in the spaced relationship shown on Fig. 1 of the drawings, on either one of the ends of the rack, while resilient locking bearings may conveniently be provided at corresponding points on the other rack end. These locking bearings severally comprise a depending rod 30 and a coacting depending rod 31 provided with an offset, journal-defining portion 32 intermediate its ends. The bearing seat defined by portion 32 is somewhat smaller than the diameter of bar 27 so that, when the latter is in place, the parts 30, 31 are slightly sprung apart and resiliently retain the bar in place. These supporting means for bar 27 are, of course, so aligned that the bar may extend through the several containers 18 and through the several reels therein, substantially as shown.

It will be understood that the aforescribed rack construction is primarily illustrative in character and that various minor modifications may be made therein without departing from the inventive concept upon which it is based.

Coming now more particularly to a description of containers 18, it will be understood that while the drawings, for the sake of clearness, show only a few of the containers, two complete rows of contiguous containers may be accommodated on the preferred form of rack according to the present invention. The rack itself may preferably be of a size such that it is portable in character and that it may readily be superposed upon a show case or the like, although the inventive concept is obviously not restricted to any particular dimensions. The containers are, of course, of a size commensurate with the rack size and, except for width which may vary according to the merchandise to be displayed and dispensed, these containers may be essential duplicates of each other.

A specimen blank or pattern for the construction of the container according to this invention is shown, by way of illustration, in Fig. 4 of the drawings. It will be understood that the dotted lines represent weakened or scored lines for folding purposes. The container blank may con-

veniently be made of cardboard or other suitable material and, as shown, comprises substantially rectangular sides 33 and 34, top 35, bottom 36, front 37 and rear 38. A pasting flap 34' is also provided adjacent top 35. This flap, in the built-up container, bears against the inside of wall 34 to which it is secured by glue or the like.

The blank additionally comprises flaps 39, 40, 41 and 42. Flaps 39, in the folded box, are bent to a position directly under rear 38; while flaps 40 assume a position directly behind front 37. Flap 41 slips into place between the sides of flaps 39 and the inner surfaces of flap 34' and of side 34 while flap 42 is arranged between the sides of flaps 40 and the inner surface of side 33.

The result is a 6-sided box or container adapted to house a roll of lace or the like which, preferably, is mounted on a central reel hub or the like 44, which may be made of wood or other suitable material. Hub 44 is preferably provided with a central bore 45 (Fig. 2) through which locking bar 27 is adapted to pass. Aligned central openings 46 of any suitable configuration are also provided for this purpose in each side 33, 34 of the container.

The bottom 36 of the container is provided with an outlet opening 47 through which the lace or other strip material may pass out of the container. The strip material is then, preferably, "threaded" through opening 54 under the front wall 37, passing therebetween and the juxtaposed flaps 40 which together are of an extent substantially equal to the extent of front 37. In order that the lace may be visible to view as it passes under front wall 37 the latter is provided with an elongated window opening 48 cut out therefrom and this window is covered by transparent material 49 such as Cellophane or the like which is adhesively secured to the portions of the container surrounding the window. Sides 33, 34 and flap 41 are provided with cut-outs 50 which align with each other when the container is folded together to define what is essentially a single cut-out into which the roll of lace or the like extends so that the quantity of material in the container may be determined by inspection. The cut-out also provides access to the material which can thus be manually actuated to rewind excess of material which may have been pulled out of the container.

Rear 38 may be cut centrally thereof to provide flaps 51, 51 which are bendable back to the position shown in Fig. 2. This is an optional expedient, however, and these flaps 51 may be entirely omitted, if desired. As shown in Fig. 1 of the drawings, the lace 43 or the like after it leaves the box 18 at the opening 52 at the front top (see Fig. 3) may be guided over rod 25 and then extend rearwardly to the back of the container 18. The last-mentioned opening 52 may readily be formed by cutting back the flaps 40 as shown at 40' (Fig. 4), providing the somewhat rearwardly displaced line of bend 52'. Opening 54 may be similarly formed with the aid of cut-backs 40' and line of bend 54'. When any container becomes exhausted, bar 27 is removed by pulling outwardly (i. e. to the right as seen in Fig. 1) at handle 28. The container to be replenished or replaced may then be withdrawn from the rear of the rack and refilled or a new filled container may be returned to the position of the removed container without essentially disturbing the set-up or any other container. The locking bar 27 is then returned to its original

place. Removal of the bar 21 may sometimes cause disalignment of partially exhausted rolls of lace or the like. In this event it may be necessary to lift these particular rolls manually through cut-out 50 to bring the corresponding bores 45 into the requisite alignment. While the containers 18 as above described are preferably to be used in association with the described supporting rack, they may nevertheless also be used apart from or independently of this rack, for example on conventional shelving. In such case, the free end of the lace, coming from the space 52 at the front top may be locked in place on the top of the box 18 through the medium of locking notch 53 which preferably is of a "keyhole" configuration, i. e. comprises a circular opening which is intersected by a V-notch. The lace or other material is pushed into the circular opening with one's finger or with a pencil or the like and it becomes wedged or locked in the said notch, thus assuring fixed retention of the material against undesired displacement. The containers may, of course, also be used individually.

It will be understood that the afore-described detailed description of the containers is primarily illustrative in character and that minor

modifications may be made therein without departing from the inventive concept upon which such construction is based.

Having described the invention, what is claimed is:

- 5 A display device of the character described, particularly adapted for displaying and dispensing lace, ribbon, braid and the like material, and consisting essentially of a one-piece blank of sheet material foldable to provide a container for housing said material to be displayed and dispensed, said blank including a section defining and constituting the front wall of said container, said section being provided with a window-opening 10 therein, a transparent cover for said opening integrally associated with said blank and extending over the entire extent of said opening, and means for defining a passageway behind and essentially coextensive with said front wall between the latter and the material in the container when the blank is folded into container form, whereby 15 the material may pass through said passageway along essentially the entire extent of said front wall.
